[57] CLAIM

The ornamental design for a lift and turn latch handle,
as shown and described.

DESCRIPTION

FIG. 1 is a perspective view of a lift and turn latch handle embodying our design with the handle element in its first position relative to the mounting element, the mounting portions which are in broken lines are for illustrative purposes only;

FIG. 2 is a top plan view thereof;

FIG. 3 is a top plan view thereof in its second position of use;

FIG. 4 is a side elevational view taken from the left of FIG. 2;

FIG. 5 is a side elevational view taken from the right right of FIG. 2;

FIG. 6 is an end elevational view taken from the bottom of FIG. 4;

FIG. 7 is an end elevational view taken from the top of FIG. 5.

FIG. 1
